UNITED STATES PATENT OFFICE

FRANK WAGNER, OF LAUREL HILL, LONG ISLAND, NEW YORK

PENCIL

Application filed October 22, 1929. Serial No. 401,429.

My invention relates to pencils of the mechanical back-turning type, in which the lead is advanced or retracted on the relative rotation of parts thereof by turning the head of 5 the pencil opposite the lead.

The object of the invention is to provide an operating mechanism for pencils of the said type which is of great simplicity, easy of assembly, certain in operation, durable and 10 economic, and which may be adapted for use in pencil casings or barrels of varying length.

In the attainment of the foregoing object I have provided a screw sleeve and a separable hollow holder therefor, with simple 15 means which cooperate to enable the said parts to be easily combined, and yet firmly held together in use, the screw sleeve being adapted to be telescoped within the holder to a greater or less extent, with all the ad- 20 vantages flowing therefrom.

The foregoing results in a very simple assembling operation, saving a great amount of labor and making a rigid joint which prevents injury to the mechanism in the assem- 25 bling operation, and by not permitting the spiral action to bend in rotating because of the perfect alinement effected, prevents the breakage of the lead inserted.

In the accompanying drawing in which 30 like reference numerals refer to correspond- ing parts,

Fig. 1 is an elevation of a pencil embodying my improvement;

Fig. 2 is a vertical section of the same show- 35 ing the parts in operative position;

Fig. 3 is an exploded view showing in sec- 40 tion the main parts illustrated in Fig. 2; and

Figs. 4 and 5 are sectional views on the correspondingly numbered lines of Fig. 2.

Referring to the drawing, a tubular barrel 45 or casing is indicated at 1, having the usual taper 2, and removable cap 3. Mounted within the barrel is the operating mechanism which consists of the screw sleeve 4, its de- tachable holder 5, tip 6, anchoring block 7 and enlargement 8, the upper end 9 of the holder 5 forming a seat for the cap 3, and the tip portion 6 being attached to the tapered end of the casing.

All of the parts mentioned are well known

in the art and are of usual construction with the exception of screw sleeve 4 and holder 5. In the screw sleeve 4 is mounted guide tube 16 the upper end of which is seen in Fig. 3 55 projecting from the screw sleeve. It is provided with a longitudinal slot 17. A clutch 18 is carried within this guide tube, is adapted to freely move therein, and is provided with a member 19 which is adapted to extend through the longitudinal slot 17 and slidably 60 engage the spiral slot 20 of the screw sleeve. The member 19 is shown in Fig. 2 extending through the uppermost end of the spiral slot. In accordance with my invention the screw sleeve is equipped with studs or extensions 65 10 and the lower part of holder 5 is contracted or reduced as shown at 11, said part 11 being provided with an internal longitudinal groove 21, the cooperative relation of these parts for the purpose desired being 70 secured by so proportioning the circumference of the screw sleeve that it will snugly fit into the bore of the contracted portion of the holder, and the studs carried by it be received in groove 21. 75

As a result of these novel departures from other constructions in the pencil art, marked advantages result. The means for holding the said parts in association are extremely simple. Nevertheless in assembling the parts 80 the assurance is certain that as soon as the contracted portion of the holder is forced over the screw sleeve and in contact with the studs 10, the screw sleeve and holder are held in firm connection and perfect alignment. 85 Furthermore these operating parts may be made to fit casings or barrels of different lengths. For use in a barrel of average pencil length the screw sleeve is inserted into the holder to the point necessary to bring the studs 10 into engagement with the holder. When intended for use in casings of shorter length the holder is forced along the screw sleeve until the combined length of the screw sleeve and holder as so adjusted will adapt 90 them for use in the size of casing desired.

At 12 is shown a safety clip. In my im- 95 proved pencil this clip is mounted without the use of rivets or prongs. It is so bent that its base or inner end 13 is passed through 100

opening 14 in the casing and is firmly clinched between the bushing 8 and casing 1.

There is nothing novel in the operation of the pencil or the mounting of the lead. It is 5 obvious that when the parts are in operative position and the lead such as 15 is inserted in the tip of the lead holder, the rotation of the cap 3 attached to the upper end 9 of the holder will advance or retract the lead as 10 desired. It is clear, too, that the holder may be used to hold extra leads, and that its enlarged end constitutes a socket for the reception of an eraser.

What I claim as new and desire to secure 15 by Letters Patent of the United States is:

In a pencil of the character described a tubular casing tapered at one end, a holder having a contracted portion adapted to be inserted therein at the untapered end, said contracted portion being provided with an internal longitudinal groove, an enlargement 20 on said holder adapted to make frictional contact with the casing adjacent the said end, an anchoring block closing the tapered end 25 of the casing and having feeding mechanism mounted on its inner end and a tip on its outer end, said feeding mechanism comprising a spirally slotted screw sleeve, a slotted guide tube within said sleeve and a clutch 30 carried within the guide tube and cooperating with said sleeve and tube by means of a member thereon extending through the slots in the guide tube and sleeve, and studs on said screw sleeve for holding the feeding mechanism and holder in adjustable alignment, 35 substantially as and for the purpose set forth.

In testimony whereof, I have signed my name to this specification.

40 FRANK WAGNER.
